UNITED STATES PATENT OFFICE

154,500

DESIGN FOR A CASING FOR SHOWER VALVE

Hugh H. Logan, La Canada, Calif.

Application November 14, 1946, Serial No. 134,789

Term of patent 14 years

(Cl. D91—3)

To all whom it may concern:

Be it known that I, Hugh H. Logan, a citizen of the United States of America, residing in the city of La Canada, in the county of Los Angeles, State of California, have invented a new, original, and ornamental Design for a Casing for Shower Valve, of which the following is a specification, reference being had to the accompanying drawings, forming a part thereof.

Fig. 1 is a top plan view of a casing for shower valve, showing my new design;

Fig. 2 is a front elevational view thereof;

Fig. 3 is a side elevational view thereof; and

Fig. 4 is a bottom plan view thereof.

I claim:

The ornamental design for a casing for shower valve, substantially as shown.

HUGH H. LOGAN.
